UNITED STATES PATENT OFFICE

2,050,891

HINGE

Gustave F. Maisch, Chicago, Ill., assignor, by
mesne assignments, to Edison General Electric
Appliance Company, Inc., a corporation of New
York

Application September 11, 1934, Serial No. 743,501

7 Claims. (Cl. 16—140)

This invention relates to hinges, and it has for its object the provision of an improved device of this character.

This invention, while it has various applications, is particularly useful to connect together members which normally are biased to one relative position, but which are movable to another or other relative positions, wherein it is desired to hold the members against the force of the biasing means. For example, this invention is particularly applicable to dishwashing apparatus wherein there is provided a vat having a cover normally resting in a horizontal closed position to which it is biased by means of its weight, and which must be elevated to an open position to provide for the insertion of soiled dishes into the vat and for the removal of the dishes from the vat after they have been cleansed. Oftentimes, apparatus of this character is placed within a kitchen in such a position that an overhanging ledge of a window sill or other obstruction prevents movement of the cover from its closed position to a position back of its perpendicular or upright position, with the result that it is necessary for the attendant to prop the cover open with an auxiliary device, or to hold it open manually while loading or unloading the vat. Both of these operations are troublesome, especially the latter, as the covers usually have considerable weight.

This invention has as one of its objects the provision of an improved hinge structure, which will function to hold the cover in its open position after it has been moved to this position by the attendant. It is a further object of this invention to provide a suitable hinge structure, which when the cover is moved to its closed position will release the cover sufficiently to permit it to adjust itself to its natural closed position.

In accordance with this invention, the hinge comprises cooperating relatively movable interconnected hinge members which are arranged to connect the relatively movable members together; thus, in the case of a dishwasher the hinge members function to connect the cover to the vat. The cooperating hinge members are provided with friction surfaces which are arranged to be moved into frictional engagement with each other, together with means that is operated responsively to the movement of the cover to its open position to move the surfaces together to generate a frictional force between the surfaces sufficient to hold the cover in its open position. The hinge is further so arranged

that when the cover is moved from its open to its closed position, the frictional force will be reduced, or substantially completely removed so that the attendant will have no difficulty in returning the cover to its closed position. Suitable means are provided for adjusting the hinge structure whereby the frictional surfaces can be moved together with more or less force depending upon the adjustment, whereby the cover can be held in various open positions at an angle to the vertical.

For a more complete understanding of this invention, reference should be had to the accompanying drawing in which Fig. 1 is a fragmentary elevation of dishwashing apparatus provided with hinges arranged in accordance with this invention; Fig. 2 is an enlarged plan view of a hinge arranged in accordance with this invention and used in the washing operations of Fig. 1; Fig. 3 is a vertical sectional view taken through the line 2—2 of Fig. 2; Fig. 4 is a vertical sectional view taken through the line 4—4 of Fig. 3 and looking in the direction of the arrows; and Fig. 5 is an expanded perspective view illustrating the various elements of the hinge shown in Figs. 3 and 4.

Referring to the drawing, this invention has been shown as applied to a hinge which is employed to connect the cover to the vat of a dishwashing machine, although it is to be understood that the hinge has general application. As shown in Fig. 1, the vat 10 is provided with a cover 10a which normally rests in a horizontal closed position, but which is movable to elevated open positions. The cover 10a is secured to the vat 10 by means of a pair of hinges 11, which are arranged in accordance with this invention, and which have the same construction.

As shown in Figs. 2—5 inclusive, each hinge comprises a hinge lug 12 which is provided with 40 upright-arms 13 secured to a base 14. It will be observed that the arms 13 are formed integrally with the base 14 and that the arms together with the base have a U-shape. The hinge lug 12 is rigidly secured to the upper wall 10b of the 45 vat 10 by means of a stud 15, which is passed through an aperture 16 provided for it in the base 14. The stud 15 is also passed through an aperture provided for it in the upper wall of the vat, as clearly shown in Figs. 3 and 4. On 50 the lower end of the stud is threaded a nut 17 which is threaded upon the stud so as to rigidly secure the hinge lug 12 to the vat.

Cooperating with the hinge lug 12 is a hinge lug 18, which is provided with a pair of arms 19

arranged relatively close to the arms 13 respectively of the lug 12. In the specific form of this invention illustrated, the arms 19 are positioned on the outside of the arms 13, as clearly shown in the drawing. The arms 19 are rigidly secured to a flat plate 20, which in turn is mechanically connected to the cover 10a of the vat by means of screws 21 passed through apertures provided for them in the plate and likewise in the cover 10a. Nuts 22 are threaded upon the studs so as to rigidly clamp the lug 18 to the cover. Preferably, the lug 18 will be provided with a hood or cover 23 between the arms 19, and which preferably will be formed integrally with the arms 15 and with the plate 20. This cover conceals the mechanism of the hinge.

It will be observed that the arms 13 and 19 have considerable areas. It is contemplated that when the cover 10a is elevated to an open position, the adjacent surfaces of these arms will be moved together so that frictional forces will be generated between them sufficient to hold the cover in its open position. For this purpose, a pair of studs 24 are mounted upon the arms 19 of the lug 18. As shown, these studs 24 are projected inwardly through apertures 25 provided for them in the arms 19 and through apertures 26 provided for them in the upright arms 13 of the lug 12. The apertures 25 in the arms 19 are given a square or other suitable non-circular cross-section, and the studs are provided with portions 27 adjacent the heads of the studs having corresponding cross-sections so that relative rotary movement between the studs 24 and the arms 19 is prevented.

Threaded upon the inner ends of the studs 24 are nuts 28 which are arranged to be turned inwardly on the studs so as to clamp the arms 13 and 19 together when the cover 10a is opened.

In order to cause the nuts 28 to thus move inwardly, suitable means are provided for preventing rotary motion of the nuts 28 relative to the hinge lug 12. For this purpose, a rotary member 29 is provided. This member, as shown, is provided with sockets 30 arranged to receive the nuts so as to prevent relative rotary motion between the nuts and the member 29, but permitting limited relative longitudinal movement between these members. As shown, the nuts 28 have a hexagonal form and the sockets are given a corresponding shape so as to prevent rotary movement between the sockets and the nuts.

Suitable means are provided for normally preventing rotary motion of the member 29 relative to the lug 12, but at the same time providing means for adjusting this member on its axis relative to the lug 12. This means comprises an adjusting screw 31 which meshes with a worm thread 32 provided on the member 29 between the two sockets 30, as clearly shown in Figs. 4 and 5. The adjusting screw 31 is carried by a U-shaped bracket 33, the legs of which straddle the worm portion 32 of the member 29, as shown clearly in Fig. 3, and which in its lower ends is provided with a pair of apertures 34 and 35 positioned below the worm 32 and which function to rotatably mount the adjusting screw 31, below the worm in meshed relation with it, as clearly shown in Fig. 3. The U-shaped bracket 33 is prevented from rotating on the axis of the member 29 by means of a head 36 arranged on the upper end of the stud 15 so as to be positioned between the lower ends of the legs of the U-shaped bracket, as clearly shown in Figs. 3 and 4. It will be observed that the positions of

the nuts 28 on the studs 24 can be varied by adjusting the position of the member 29 by turning the screw 31.

It will be understood in view of the foregoing description, that when the cover 10a is elevated, the nuts 28 will be moved outwardly to cause the arms 13 and 19 to move together, and that the nuts will have been positioned initially upon their studs 24 so that when the cover is opened, the frictional forces generated between the arms 10 will be sufficient to hold the cover in its open position. The arms are sufficiently flexible to permit the nuts to move them together.

It will also be understood that the magnitude of these frictional forces will depend upon the initial adjustment of the nuts 28 by the screw 31. The adjustment given the nuts will depend upon the angle the cover 10a has in its open position. If the cover be nearly vertical when open, the frictional forces between the arms 13 and 19 need not be so great as is necessary to support the cover in an open position at a considerable angle to the vertical. If the screw 31 is adjusted to move the nuts 28 inwardly on the studs 24 so as to provide an initial frictional force between the arms 13 and 19, this force will be correspondingly increased when the cover is elevated so that the cover can be supported at a considerable angle to the perpendicular. On the contrary, if the nuts 28 are moved outwardly on their studs 24 by the screw 31, the frictional forces generated between the arms 13 and 19 when the cover is moved to its open position will be reduced so that the cover cannot be supported at such a great angle to the vertical. Any suitable frictional force between the arms 13 and 19 may be obtained within a wide range by adjusting the screw 31, so that the cover 10a can be held in any open position within a wide range of movement.

It will be observed, however, that in any case, when the cover is returned from its open to closed position, the nuts will be turned outwardly on the studs 24 to reduce the frictional forces between the arms 13 and 19 so that it does not require any undue effort on the part of the attendant to close the cover.

Preferably, the openings 26 in the arms 13 of the lug 12 will be elongated in the vertical direction, as viewed in Figs. 3, 4 and 5, so that the hinge lugs 12 and 18 can move relatively to each other sufficiently to permit the cover 10a to adjust itself to its normal closed position.

Another feature of this invention is the provision of suitable means in the hinge structure for venting the dish-washing vat. For this purpose, the flat-plate portion 20 of each hinge lug 18 is provided with a relatively large aperture 37 which registers with a similar aperture 38 arranged below it in the cover 10a, as shown in Fig. 3. The aperture 37 is covered by means of a suitable casing 39 secured to the hinge member by means of tongues 40 provided on the casing and received in apertures or slits 41 provided for them in the hinge lug, as clearly shown in Figs. 3 and 5. This casing member 39 is provided in its sides with elongated apertures 42. Preferably, a suitable baffle or deflector 43 will be provided below the aperture 38 provided in the cover to prevent the flow of water or cleansing fluid outwardly through the hinge.

While this invention has been shown as applied to the cover of dishwashing apparatus, it is understood that it has general applica- 75

tion. For example, it may be used to hinge a door to its casing, and it is particularly useful in this application where it is desired that the door be positively held in its open position.

5 While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

10 What I claim as new and desire to secure by Letters Patent of the United States is:

15 1. A hinge structure comprising a plurality of relatively movable members, friction members associated with said movable members respectively arranged to engage each other, and means operated responsively to relative movement between said members controlling the magnitude of the frictional force between said friction members so that when said movable members are moved from one predetermined relative position to another said frictional force gradually increases to a relatively large holding value, and 20 is substantially relieved when said members are returned to said one relative position.

25 2. A hinge structure comprising a pair of pivotally interconnected relatively movable members provided with relatively large substantially parallel flexible surfaces arranged to frictionally bear on each other, and means for moving said flexible surfaces together to generate a frictional force of increasing magnitude between them responsively to relative pivotal movement of said members in one direction from one 30 relative position to another, and for substantially relieving said frictional force responsively to relative pivotal movement of said members in the opposite direction from said other to said one relative position.

35 3. A hinge structure comprising a pair of hinge lugs having cooperating flexible members arranged to frictionally engage each other, means pivotally connecting said hinge lugs together, means responsive to relative movement of said lugs in one direction forcing said flexible members into frictional engagement with each other to generate a frictional holding force between them and substantially relieving said 40 force when said lugs are moved relatively in the opposite direction.

45 4. A hinge structure comprising a pair of hinge lugs having flexible metallic members provided with cooperating plain surfaces arranged to be moved into frictional engagement with each other, threaded members secured to said flexible members on one of said lugs, nuts on said threaded members arranged to be moved thereon to force said flexible members together, and means preventing relative rotary motion 50 between said nuts and said other of said lugs so that when said lugs are moved relative to each other in a predetermined direction, said nuts are operated to move said surfaces together into frictional engagement with each other.

55 5. A hinge structure comprising a hinge lug, a second hinge lug, said lugs having flexible metallic members provided with cooperating

plain surfaces arranged to be moved into frictional engagement with each other, threaded studs secured to said flexible members on one of said lugs, nuts threaded on said studs adjacent said cooperating flexible members arranged to be moved on said studs to force said surfaces together, means preventing relative rotary motion between said nuts and the other of said lugs so that when said lugs are moved relative to each other said nuts are operated to move 10 said surfaces together into frictional engagement with each other, and means for rotating said nuts relative to said other lug to vary the frictional force between said members when said member is elevated.

15 6. A hinge structure comprising a hinge lug having a pair of upright flexible arms, a second hinge lug having a pair of flexible arms positioned outside of and relatively close to said upright arms respectively of said first lug, studs 20 mounted on the arms of said second lug and projected inwardly through apertures in the arms of said first lug, means preventing relative rotary movement between said studs and said arms of said second lug, nuts on said studs, a rotary 25 member positioned on the axis of said studs provided with sockets arranged to receive said nuts so as to prevent relative rotary movement between said nuts and said rotary member, but providing for limited relative longitudinal movement between said nuts and said member, and means securing said rotary member from moving relative to said first lug so that when said lugs are moved relative to each other said nuts are threaded outwardly on said studs to force 30 said flexible arms into frictional engagement with each other, said means comprising a worm on said rotary member, a screw meshing with said worm, and means securing said screw to said first lug to normally prevent relative rotary 35 movement of said rotary member on the axis of said studs relative to said first lug, said screw being adjustable to vary the position of said rotary member on said axis.

40 7. A hinge structure comprising a hinge lug 45 having a pair of upright flexible arms, a second hinge lug having a pair of flexible arms positioned relatively close to the upright arms of said first lug, studs carried by said flexible arms of said second lug passing through apertures 50 provided for them in said upright arms, means preventing relative rotary motion of said studs on their axes relative to said arms of said second lug, nuts on said studs arranged when rotated on said studs to force said upright and said 55 arms of said second lug into frictional engagement with each other, and means preventing rotary motion of said nuts relative to said upright arms so that when said lugs are moved relative to each other in one direction, said 60 nuts are moved on said studs to move said arms into frictional engagement, and for releasing said arms to reduce the frictional force between them when said lugs are moved in the opposite direction, the apertures in said upright arms 65 being elongated vertically to provide for limited relative vertical movement between said lugs.

GUSTAVE F. MAISCH.
